DATA CONVERSION OPERATION
BOYERS, PA

George Page of Keene New Hampshire
Latters Patent (Patented March 18, 1836)

This Schedule referred to in these Letters Patent and making part of the same containing a description in the words of the said George Page himself of his improvement in the machine for mortising small timber.

To all persons to whom these presents shall come, & be it known that I George Page of Keene in the County of Cheshire and State of New Hampshire have invented a new and useful improvement in the method of mortising by a machine, which machine is described as follows. The bottom consists of two pieces of old work four inches wide: the one which is thick, one piece three feet long, the other piece three feet and four inches, these are bolted together as follows: each other at right angles. The plan of intersection in the shortest piece being at equal distances from each end and in the longest piece about two feet from one end the short end being at the front of the machine. At the place of intersection a mortise is made into which by a tenon is fixed an upright post four inches square and sixteen feet high from the bottom of the side. Beginning at three inches from the top of the side, a mortise is made in the direction of the longest side through this post one inch wide and eleven inches long. Up to the end of the long side behind the post is fixed by a mortise an iron upright post four inches wide two inches thick and seventeen inches high from the bottom of the side. In the top of this post one end of a lever is inserted a foot passing thro' the post and end of the lever which lever passes thro' the mortise in the end of the post and has upon the other end a piece of board upon which to place the foot, also another above the mortise in the post another mortise is made thro' it in the same direction four eighths of an inch wide and fifteen inches long thro' this mortise passes two movable iron bolts with a screw collar and nut on one end of each: one of these bolts passes thro' a piece of leather called a Rest and has a head ^{at} that end. Thro' the other

end of the other will, a hole is made third which passes, and is in the shape of a segment of a circle, each end of which is, attached to the lower side of the chest. This rod is from two to two & a half feet long, & four inches broad at base. (By means of two bolts, screws, &c.) The chest may be made fast and steady, at any desired height, or inclination. A board three inches and a half wide is let into the post, even with the face of it, and crossing it, the upper edge being two inches above the top of the mortise, the board being set away against the mortise. Near the top of the board a slot or piece of iron is screwed firmly to the post to prevent the lumber from swinging by the operation of the machine. About four feet three inches from the bottom of the wills a brace of the edge of the post and three feet long is inserted in the post inclining forwards at an angle of nearly two degrees from a horizontal line. This brace is made steady by a girl or an iron rod with a screw and nut on one end and a head on the other passing through it and the post near the top of the latter. Beginning five feet nine inches from the bottom of the wills another mortise is made thro' the post, in the same direction as those below, an inch wide and eight inches long. A similar mortise level with this is made thro' the brace. To the outside of the brace below the mortise is fastened ^{by screws} a piece of cast iron shaped like & having a horizontal hole thro' the projecting end. This by means of two flat pieces of iron eight or ten inches long is connected with the end of a lever which passes thro' the mortise in the brace and post, and is about two feet nine inches long. Back of the post several holes are made horizontally thro' this lever and corresponding holes thro' the board first mentioned. A rod will be placed at each end connecting the two levers, the pins being placed thro' each of the holes, as will give the purchase and motion wanted. The end of a spring made of hickory root or other elastic lumber is inserted in a mortise near the top of the brace and passing thro' the top of the post is

connected with the upper lever at the end by a leather strap having a buckle by which it may be tightened or loosened at pleasure. An important part of the machine, is a slide which is a rod of iron polished round seven eighths of an inch in diameter and two feet four inches long. Into the lower end a hole is drilled longitudinally two inches deep to receive as a socket for the chisel. About two inches from the lower end in front a hole or mortise half an inch long and three sixteenths wide is made this is to which the chisel may be keyed or driven. About two inches from the lower end on one side is a small hole also drilled through it, and from and a half inches above and below into which is inserted and fastened the base and of a square wire or guide. Into the top of the slide a hole is also drilled two inches deep into which a bolt is inserted and fastened by a pin. This bolt has a head shaped like half a globe or ball the top being round and with pins projecting at opposite sides, called a yoke. Surrounding the bolt between the head and the slide the pins going thro' the end, of a circ. which passes over the upper lever near the post. To the lower side of this lever is fastened an iron plate, into which a hole is countersunk to receive the head of the bolt, which is drawn up into it by a wedge driven between the upper side of the lever and the lever. About two inches below this lever the slide passes thro' a box shaped thus . This projection is inserted in a hole thro' the post. Against this hole on the left side a mortise is made into the post and a small hole is bored to the mortise from the right side. A hold fast being a screw with an eye on one end and a thumb nut on the other is introduced into the mortise and hole; the projection of the box passing through the eye. By means of this the slide may be set at any desired distance from the post. The slide then passes down through a hole in the brace, and about two inches above the lower end of the slide it passes thro' another box constructed thus. It consists of several parts and is made of cast iron. One part is shaped thus and the other thus . The length of the large piece from a to b, is about six inches, the general thickness three fourths of an inch, a side or projection rising at the edges, a and b. The part, c,

is inserted in a hole thro' the post, and made fast in the same way as the upper box before described. The smaller piece is the same thickness, a little shorter, and is connected ^{by} the larger discus, so that the two half circles form a hole or box an inch and a quarter in diameter. Within this an inner box: the hole thro' which is seven eighths of an inch in diameter being the same as that of the slide. It has a perpendicular groove cut on one side, for the square wire or guide to run in. It is an inch and a half long and has a groove inclosing it on the outside as wide as the two first described parts are thick, and so deep that the fast thus made smaller may be received, and turn within the outer box. At the upper end of this inner box on one side, outside, is a small projection one fourth of an inch long, round half an inch in diameter with a hole made into it longitudinally to receive one end of a small spring or catch. By this spring or catch the slide may be turned half round and may be kept steady in place by letting the catch fall into a small groove or notch made in the ribs, or projections above mentioned. The machine should be set up on the right side of a stud or post and bolted to it, and if convenient a long spring may be used fastened to a joist above instead of the short one attached to the machine. When the machine is to be used the movable rest is adjusted and made fast at the proper place to admit the wood to be mortised between the rest and the tool on the post. The wood to be mortised is ~~to~~ placed on the rest, the wheel is set to cut either head of the mortise, the lower lever is scraped down by the foot which brings down the upper lever to which the slide is attached, and driving the chisel into the wood. The foot being raised the spring at the top withdraws the slide from the wood, which is then moved, and the foot applied as before and so on until one head of the mortise is finished. By means of the spring or catch, the slide is then turned half round, and the other head of the mortise is finished by a similar operation. It will be noted that one end of the rest should be raised or lowered by means of the segment of a circle or circular brace below it. That is claimed as my own invention and not previously known in the above described machine etc. is the mode of attaching the slide to the upper box and that lever to the machine, and also the
upper box and the circular brace as herein described
